OTHER PUBLICATIONS

U.S. Appl. No. 14/104,286, filed Dec. 12, 2013, Hassett.
(Continued)*Primary Examiner* — Sheryl Lane*Assistant Examiner* — Ieisha Price(74) *Attorney, Agent, or Firm* — Sheridan Ross, P.C.(57) **CLAIM**

The ornamental design for a protective case, as shown and described.

DESCRIPTION

FIG. 1 is a front perspective view of a protective case;
FIG. 2 is a top plan view thereof;
FIG. 3 is a left elevation view thereof;
FIG. 4 is a front elevation view thereof;
FIG. 5 is a right elevation view thereof;
FIG. 6 is a rear elevation view thereof;
FIG. 7 is a bottom plan view thereof; and,
FIG. 8 is a front elevation view thereof, shown in an open position;
The broken lines in the drawings illustrate portions of the
protective case and form no part of the claimed design.
